UNITED STATES PATENT OFFICE

95,933

DESIGN FOR A TEXTILE FABRIC OR SIMILAR ARTICLE OF MANUFACTURE

Albert Schumacher, Passaic, N. J., assignor to
Botany Worsted Mills, Passaic, N. J., a corporation of New Jersey

Application February 7, 1935, Serial No. 55,294

Term of patent 14 years

To all whom it may concern:

Be it known that I, Albert Schumacher, a citizen of the United States of America, residing at No. 40 Reid Avenue, in the city of Passaic, State of New Jersey, have invented a new, original, and ornamental Design for a Textile Fabric or Similar Article of Manufacture, of which the following is a specification, reference being had to the accompanying drawing, forming a part thereof, in which Fig. 1 shows a face view of a piece of textile fabric embodying my design, while Fig. 2 is a cross section along line 2—2 of Fig. 1.

The characteristic features of the design reside

in rows of substantially straight parallel grooves cut into the nap of a fabric, said grooves comprising series of annular portions and straight portions, said straight portions connecting the individual annular portions within each row with one another, said grooves being uniformly and regularly arranged in staggered relation with respect to each other.

I claim:

The ornamental design for a textile fabric or similar article of manufacture substantially as shown and described.

ALBERT SCHUMACHER.
